UNITED STATES PATENT OFFICE

EDUARDO T. VILLASENOR, OF NEW YORK, N. Y.

COLLAR PROTECTOR

Application filed October 25, 1928, Serial No. 314,986, and in Mexico November 29, 1927.

This invention relates to protectors for coat collars.

In tropical climates persons who have to wear coats, experience discomfort and annoyance by excessive perspiration which soils the collars of their coats. Grease and oil from the hair of the wearer also soils the coat collar.

One object of my invention is to provide protection for the coat collar edge by means of a flexible covering made preferably of some stiff material, which may have a certain amount of resiliency, designed to overlap the edge of the collar on the inner and outer sides. To provide for great flexibility the covering may be made in sections which may be hinged together. By this means the wearer experiences no discomfort while wearing the protector and will be able to remove his coat with ease.

Other objects will appear as my collar protector is described in connection with the annexed drawings in which—

Figure 1 is a front perspective of a coat having one of my collar protectors thereon;

Fig. 2 is a rear perspective of the preferred form of my collar protector removed from the coat and with the wedge rods removed. The dotted lines in this figure show the protector in expanded position;

Fig. 3 is a front elevation of the hinge joint between two sections of my protector partly broken away;

Fig. 4 is an elevation taken on line 4—4 of Fig. 1;

Fig. 5 is a front elevation of another form of my protector in expanded position;

Fig. 6 is a front elevation of a coat collar prepared for fastening thereon the form of protector showing in Fig. 3;

Fig. 7 is an elevation section taken on line 7—7 to Fig. 5, but showing in addition the coat collar within the protector.

The protector is made by taking a relatively long flat rectangular strip of stock of the material and bending this strip into a channel-like form having a U-shaped cross-section. Then the channel is curved to follow the contour of the folded edge of the collar. The length and width of the strip

used to form this construction will depend on the amount of overlap desired on each side of the collar edge and on the amount of the collar edge to be protected.

Referring now to the drawings it will be noted that my protector extends around the edge of the coat collar 5 in such a way as to protect it from grease and perspiration. The protector extends from a point 6 on the edge of the collar just over the collar bone on one side, around the back of the collar to a point 6' just over the collar bone on the other side of the collar. Thus the protector is semi-circular in shape but to follow the contour of the edge of the collar as it lies on the neck of the wearer, the ends of the protector are usually given a twist so that the protector ends will lie flat over the collar bone of the wearer.

To provide for great flexibility of the protector I make it in a plurality of sections 1, 2, 3, 4 and hinge the adjacent sections together. Any conventional type of hinge joint 20 may be used but I prefer to use a hinge made of sheet of rubber or leather or

other pliable material. When employing my preferred type of hinge I make each of the sections 1, 2, 3, 4 of my protector of thin stock doubled over on itself to make the material of two ply in thickness before forming it as described above. At the end of each section in the thin space, that is to say, in the fold between and resulting from the doubling over of the stock, one-half of a small thin sheet or hinge member 9 of leather or elastic rubber of suitable dimensions is interposed and is secured thereto by any suitable means, for example, by cementing or riveting. Only one-half of the rubber or leather sheet is interposed in each section in order that the other half be allowed to extend beyond the end of the section and into a corresponding space or fold in the adjacent section to which it will be secured in a manner similar to that already described for the first mentioned section. Thus a flexible hinge joint is formed.

It should be noted that in forming the hinged joint between the protector sections the flexible sheet extends up the outside of

the protector to the bend of the fold but it does not follow the edge of the collar to the inside.

To provide greater strength, and to insure longer life and additional firmness of the hinge joint, I extend the exterior corners 10 of each section downwardly and carry the hinge member 9 down into the corners.

The two end sections 1 and 4 of the protector are, at their unhinged ends, extended by short tongues 12 which follow the contour of the edge of the collar to give a finished appearance to the protector.

In Fig. 4 I have shown a preferred form 15 of fastening means which does not require mutilation of the coat. In this construction the collar edge is slid in the protector and maintained there by a wedging action due to the side ribs 16 which run along the edges 20 of the protector on the inside of each section and end short of the section end. These ribs may be formed by securing to the protector, as by cementation or fusion, tubular or wire like segments running a portion of 25 the length of such section and made of the same material as the main portion of the protector or any other suitable substance.

In the fold of the collar a long flexible 30 rod 17 may be inserted to assist in holding the protector on the collar, the length of which rod may be the length of a section, a separate rod being used for each section. The collar is held firmly in the protector due to the thickness of the cloth of the collar 35 and the wedging action which is present by virtue of the ribs 16 and rod 17.

Another method of fastening the protector to the collar is by snap fasteners consisting of downwardly facing plug members 14 rigidly 40 secured inside the protector at its top to cooperate with spring socket members 15 incorporated into the edge of the coat collar at suitable points. As many fasteners as desired may be used. If desired a fastener 45 may be placed on each tongue 12.

My collar protector may be made of fibre, celluloid, metal or any other similar substance or material which is characterized by stiffness but has sufficient resiliency to avoid 50 rigidity.

My collar protector need not necessarily be made of stock of two ply in thickness but may be made of a single thickness or ply formed and shaped in the manner described 55 and with the hinge members and ribs suitably secured to the interior of the protector by riveting or adhesion.

Many changes in shape, form and assembly within the scope of my invention will 60 occur to those skilled in the art.

Having described my invention I now claim and desire to secure by Letters Patent:—

1. A coat collar protector, characterized 65 by its stiffness and composed of a plurality

of channel shaped, connected, arcuate sections, each section having two longitudinally extending ribs therein to hold the protector in position upon the collar.

2. A coat collar protector, characterized 70 by its stiffness and composed of a plurality of channel shaped, connected, arcuate sections, each section having two longitudinally extending ribs therein, and wedge means adapted to cooperate with a collar and said 75 ribs to hold said protector on the collar.

3. A coat collar protector, characterized 80 by its stiffness and composed of a plurality of channel shaped, connected, arcuate sections each section having two longitudinally extending ribs therein and an elongated flexible wedge adapted to cooperate with a collar and said protector to hold said protector in position upon the collar.

4. A coat collar protector, consisting of a 85 plurality of channel shaped, arcuate sections formed of two ply stock, flexible hinge joints between adjacent sections composed of flexible hinge elements interposed and secured between the plies of the respective sections. 90

In testimony whereof I have signed my name to this specification.

EDUARDO T. VILLASENOR.
